UNITED STATES PATENT OFFICE.

WILLARD IRVING TWOMBLY, OF NEW YORK, N. Y., ASSIGNEE, BY MESNE ASSIGNMENTS, TO D. STUART DODGE, OF WEATOGUE, CONNECTICUT.

AEROPLANE.

1,322,976.

Specification of Letters Patent. Patented Nov. 25, 1919.

Application filed December 4, 1911, Serial No. 663,873. Renewed April 16, 1919. Serial No. 290,640.

To all whom it may concern:

Be it known that I, WILLARD IRVING TWOMBLY, a citizen of the United States, residing in the borough of Manhattan, in 5 the city, county, and State of New York, have invented new and useful Improvements in Aeroplanes, of which the following is a specification.

This invention relates to aeroplanes, and 10 it is the principal object of the invention to provide a plurality of separate and independent power plants or motors either one or all of which may be utilized to operate the propelling means, and to provide means 15 actuated by the motors to operatively connect either one or all of said motors with the propelling means as they are started, and as either one or all of the motors are stopped to automatically throw them out of 20 operative connection with the propelling means.

A further object of the invention relates to the general construction of an aeroplane of the monoplane type, and to give to the 25 fuselage and the supporting planes such shape and curvature as to decrease to a minimum the head resistance of the aeroplane and whereby it will be self sustaining or lifting in flight, for which purpose I provide 30 a central longitudinal fuselage entirely covered carrying an elevating plane and a rudder at the rear end. The bottom of the fuselage commencing at the head to the tail is of concave formation merging into a convexed portion, and said latter portion 35 merging into a plane or flat portion extending to the end; while the top commencing at the forward end is of convexed formation and then merges into a plane or flat portion 40 which extends to the rear end, with the forward portion of the top and the bottom merging or joining together substantially in a point. A pair of rigid lateral supporting planes are fixed to the fuselage, the said 45 planes from the front and extending to the rear viewed from the bottom being of concaved formation and adjacent the rear of convexed formation and tapering from the front toward the rear, with the front edges 50 in a plane higher than the rear edges, and tapering from the fuselage out to the ends.

Another object of the invention relates to improved means to maintain lateral balance or equilibrium, comprising ailerons

located at the ends of the plane or planes 55 and fixed to shafts rotatably carried by the plane or planes, means being provided to impart rotary motion to said shafts simultaneously in opposite directions, to adjust the ailerons to different angular positions 60 relative to the plane or planes and to each other to present different angles of incidence to the atmosphere.

A further object of the invention relates to an improved starting and alighting carriage, comprising a series of standards constituting a part of the framework having skids fixed thereto, said skids inclining toward the rear with the forward ends curved upwardly and extending beyond the forward end of the aeroplane. The aeroplane is normally supported when on the ground by a pair of wheels connected to the ends of a resilient member extending transversely of 70 and secured to the skids in such manner as to permit it to have a slight endwise movement when it is sprung or flexed by the aeroplane in alighting, suitable means being provided to prevent undue endwise movement of said resilient member. 75

In aeroplanes as heretofore constructed in order to start or set the power plant, usually consisting of an internal combustion engine in operation, rotary motion is imparted to the propelling means by an attendant, 80 which is a dangerous operation due to the back-firing and other causes, and it is a further object of the invention to provide means whereby the motor may be cranked from the seat of the aviator, for which purpose I provide a suitable clutch between the motor and the propelling means, an actuating lever being connected thereto and located conveniently to the seat of the aviator. By 85 moving the lever in one direction the clutch is thrown into operative engagement and rotary motion imparted to the motor, and said clutch is thrown out of operative engagement after the motor is started or the lever reaches the limit of its movement and is returned to initial position. 90

In aeroplanes of this type the plane supporting or stay wires as well as the control wires are all exposed, not only being exposed to the deteriorating effect of the elements but often tampered with by unauthorized persons with disastrous results to the aviator, and it is a further object of the 100 105

invention to construct an aeroplane in which all of the supporting or stay, as well as the control, wires are inclosed either in the framework or the fuselage.

5 Other objects and advantages will herein-after appear.

As a preface to a detail description of the figures of the drawings, I wish to say that while my invention is shown in connection with an aeroplane of the monoplane type, it will be obvious that certain features of the invention are applicable to aeroplanes of different construction, such as biplanes, without departing from the scope of my invention.

In the drawings accompanying and forming a part of this specification, Figure 1 is a side elevation of my improved aeroplane.

Fig. 2 is a front elevation with a portion 20 of one of the wings broken away.

Fig. 3 is a side elevation of a detail of the means for starting the motor from the seat of the aviator.

Fig. 4 is a detail to show the mounting 25 of the lever to operate the motor starting means.

Fig. 5 is a fragmentary side elevation of a detail of the motor-starting means.

Fig. 6 is a plan view of my improved 30 aeroplane.

Figs. 7 and 8 are sectional detail views of the means to connect the resilient supporting member to the alighting carriage.

Fig. 9 is a detail illustrating the manner 35 of connecting a propelling driving shaft to the forward ends of the plane.

Fig. 10 is an enlarged sectional detail view illustrating a bracket in which the propeller and its driving shaft are journaled.

40 Fig. 11 is a front elevation, partly in section, to illustrate the mounting of the power plant and the manner of connecting the same to the propeller-driving shaft.

Fig. 12 is an end elevation of one of the 45 brackets in which the propeller and its driving shaft are journaled and the manner of connecting a plane support thereto.

Fig. 13 is a sectional detail view of the propeller driving shaft and the means 50 whereby the motor is automatically connected thereto as it is started, and also showing the means to crank the motor.

Fig. 14 is a sectional end elevation of the propeller driving shaft and the means to 55 automatically connect and disconnect a motor thereto when started or stopped.

Fig. 15 is a plan view of the front portion of the aeroplane to illustrate the manner of supporting ailerons at the ends of 60 the supporting planes whereby to maintain lateral balancing or equilibrium, and the means to adjust said ailerons, said view illustrating the ailerons adjusted to different angular positions in full lines and in 65 dotted lines in their normal position.

Fig. 16 is a sectional side elevation of a portion of the aeroplane to illustrate mounting of the means to adjust the ailerons to different angular positions and to actuate the elevating plane.

Fig. 17 is a front elevation of the mechanism shown in Fig. 16; and

Fig. 18 is a plan view of the elevating plane and rudder carried at the rear of the fuselage.

Similar characters of reference designate like parts throughout the different views of the drawings.

In the embodiment of my invention illustrated in the drawings, I have shown the same in connection with an aeroplane of the monoplane type, comprising a central longitudinal fuselage or main frame, (designated in a general way by F,) consisting of spars 19, uprights or standards 20, cross bars 21 and braces or stay wires 22. The fuselage is entirely covered with a suitable material with the exception of an opening for the aviator and provided with a bird-like tail 23, and a vertical fin 24, and carrying an elevating plane 25 as well as a rudder 26 at the rear end. The standards 20 at the forward end or head of the fuselage project below the bottom of the fuselage to constitute a portion of the alighting and starting carriage, and have skids 27 fixed thereto, said skids inclining toward the rear to act as a brake to retard the movement of the aeroplane in alighting, and having their forward ends curved upwardly and projecting beyond the forward end of the fuselage to prevent the aeroplane from canting forward or turning turtle should it strike an obstruction and be brought to an abrupt stop in alighting. The aeroplane

when upon the ground is normally supported upon a pair of wheels 28 connected to the ends of a resilient or springy member 29, in the nature of a spring board of one or more layers of springy material such as metal or wood, so that in alighting when the wheels come in contact with the ground the shock of the weight of the aeroplane will be cushioned or absorbed by said member. The member 29 is connected to the skids in such manner that when it is sprung it may have a slight endwise movement and for this purpose I fix to each of the skids a pair of brackets 30, said brackets carrying a pair of rollers 31 between which the resilient member engages. To prevent undue endwise movement of said member 29 I provide it with guides 32 to slidably engage at either side of the skids. The wheels are connected to the member 29 by knuckles 33 so that said wheels may have movement on an axis perpendicular to their axis of revolution, and the knuckles connected by a rod 34 to always keep the wheels in the same plane and symmetrical with the fuselage,

and whereby any diverging movement of one of the wheels will be imparted to the other wheel through said member.

Rigid planes 35 are fixed to the forward 5 end of and project laterally from the fuselage, the lateral ends of which planes are rigidly supported by tubular upwardly projecting and laterally diverging braces 36 which may form a part of or be fixed to the 10 alighting carriage. The free ends of the braces are connected to a horizontal member 37 by couplings 37' and said member 37 is connected to the planes by means of an intermediate member 38. To adjust the planes 15 and maintain them in adjusted position, cables 39 are passed through the tubular members, said cables having screw threaded heads 40 fixed to the free ends upon which engage lock nuts 41, as clearly shown in 20 Fig. 12. Should it be found that the planes are not symmetrical due to structural strains or otherwise, it is only necessary to screw up the nuts on one end of the cables and loosen the nuts at the other ends thereby drawing 25 down one end of one plane and permitting the end of the other to move upwardly.

As already stated the fuselage and supporting planes are so shaped and curved as to decrease to a minimum the head resistance, whereby the aeroplane will be self sustaining or lifting in flight, for which purpose the bottom of the forward end or head of the fuselage is of concave formation merging into a convex portion, and which latter 35 portion merges into a plane or flat surface to the end, and the top of the forward or head portion is convex then merging into a substantially flat surface inclining toward the end, with the forward top convex and 40 the bottom concave portions merging or joining together in a point, as clearly shown in Fig. 1. By this construction as the aeroplane is propelled through the air, the air current striking against the bottom concavo- 45 convex portion will lift or sustain the forward end of the aeroplane, and the air as it is deflected from the bottom convex portion will tend to create a vacuum at the rear of the convex portion where it merges into the 50 flat portion, and the air rushing from the rear to replace said vacuum tending to cause the air currents to form eddies creating a lifting force beneath the fuselage and the tail 23. Not only is a lifting force created 55 at the bottom, but the air which is deflected from the top convex portion will form eddies where said portion merges with the flat inclined portion creating a lifting force at the top.

60 The bottom of the planes from the front to the rear edges is substantially symmetrical with the formation of the body, with the top and bottom surfaces merging in a point at the rear edges. The bottom of the 65 planes is substantially symmetrical from the

fuselage out with the top tapering or inclining from the fuselage out to the ends, as shown in Fig. 2, and with the forward edges in a plane higher than the rear edges. By this construction the air deflected from 70 the bottom concave portion will create a lifting force at the rear bottom portion of the planes and the air deflected from the top convex portion will tend to create a lifting force at the top of the concave portion of the planes. 75

To maintain lateral balance or equilibrium, I provide adjustable ailerons 42 at the ends of the planes, substantially symmetrical in formation with the planes, fixed 80 to shafts 43 rotatably carried at the bottom of the planes with the inner ends journaled in brackets fixed to the fuselage. To secure the ailerons to the shafts I fix to one of the ribs of said ailerons lugs 45 and pass a pin 85 46 transversely through the shaft with the ends engaging in said lugs. To adjust said ailerons to different angular positions relative to the planes and to each other whereby to present different angles of incidence to 90 the atmosphere, I provide means to rotate said shafts simultaneously in opposite directions, comprising a rock shaft 47 the axis of which is transverse to the axes of the aileron shafts. The shaft 47 is provided with a pair of arms 48 connected by links 49 having a universal connection with said arms 48 and arms 50 fixed to the aileron shafts. To impart rotary movement to the shaft 47 I provide a lever 51 so connected 100 thereto that when it is moved to the left, as shown in Fig. 15, rotary motion will be imparted to the aileron shafts 43 in opposite directions, and when moved to the right, as shown in Fig. 17, a reverse motion will be 105 imparted to said shafts. Said lever 51 also controls the elevating plane 25 mounted at the rear of the fuselage to be adjustable on a horizontal axis and for this purpose the shaft 47 is provided with a cut out portion 110 52 in which the lever 51 is pivotally mounted to swing on an axis transverse to the axis of said shaft. Said lever has forwardly and rearwardly projecting arms to which the control wires 53 of the elevating planes are 115 connected. By this construction it will be noted that if any sidewise movement is imparted to the lever 51 no motion will be imparted to the elevating plane 25, and that any movement of the lever on its pivot will 120 not impart any movement to the ailerons.

By this construction lateral balance is controlled without the use of the steering rudder 26 as is the usual practice now in connection with warping planes. Should 125 the right hand plane or side of the machine for any cause be tilted downward to right the machine all that is necessary is to move the lever 51 to the left, as shown in Fig. 15, thereby tilting the forward 130

end of the aileron at the right upward and the rear end downward, increasing the angle of incidence and thus causing the air to lift this side of the aeroplane, 5 while the forward end of the aileron at the left hand side is simultaneously tilted downward with the rear end upward, the air striking against the top of the aileron tending to depress this side of the aeroplane, 10 thereby causing the aeroplane to be moved on its longitudinal horizontal axis. By this construction as the machine is righted due to the increasing of the angle of incidence at one end of the planes and 15 decreasing the angle at the other end of the planes there is no tendency of the machine to turn on a vertical axis.

The propelling means consists of a pair of propellers 54 located directly in front of 20 and rotating on axes in a plane with the leading edges of the planes, with the pitch of the propeller blades so determined that the propellers revolve in opposite directions but toward each other. The propellers 25 are fixed upon stud shafts 55 journaled in journal boxes 56 fixed to the ends of the forward diagonal braces 36 and the forward ends of the braces 37. Gears 57 fixed to the shafts 55 within the boxes mesh with 30 gears 58, also within said boxes, fixed to the ends of a propeller-driving shaft 59 extending along the leading edges of the planes whereby to drive the propellers synchronously. The shaft is journaled at its ends in 35 the boxes 56 and inclosed in tubular housings 60 the outer ends of which are fixed in the boxes 56 and the other ends in brackets 66 fixed to the forward standards of the fuselage, and by brackets 61 to the leading 40 edges of the planes, as shown in Fig. 9.

As already stated one of the main features of the invention is the provision of a plurality of power plants or motors either one or all of which may be automatically thrown 45 into operative connection with the propelling means as they are started to operate said propelling means from either one or all of the motors, and automatically thrown out of connection when stopped. As is well 50 known in order to maintain the aeroplane in the air it is necessary to provide means to effect an onward movement of the aeroplane in the air at a certain velocity. In aeroplanes as heretofore constructed it has 55 been the practice to provide a power plant consisting of a single unit, invariably an internal combustion engine, and should the engine become stalled while in the air unless the aeroplane is at a considerable height to 60 enable the aviator to volplane to the ground this stalling of the motor will result disastrously. To overcome this disadvantage I provide a plurality of power plants or units, in the present instance shown as a pair of rotary internal combustion engines, (desig- 65

nated in a general way by M,) which may be of the type disclosed in my co-pending application filed October 23, 1911, Serial No. 656,317, although it will be obvious that stationary motors may be utilized. The motors 70 are rotatably mounted on crank shafts 63 having no communication with each other and connected with a suitable source of fuel supply, as at 62. The shafts are fixed in brackets 64 fixed to the forward supporting 75 standards 20 and in an intermediate support or brace 65 which at its lower end is supported upon the upwardly projecting and laterally diverging braces 36, and the shaft 59 journaled in its upper end. It will 80 be noted that the propeller-driving shaft 59 and the motors rotate on parallel axes transverse to the line of flight, and in a direction toward the front of the aeroplane.

The motors are connected to the propeller-driving shaft 59 by means of sprocket chains 67 passing around sprockets 68' fixed to the motor and sprockets 68 constituting part of overriding clutches fixed on the shafts 59. These clutches are so constructed that when 90 the motors are started they will be automatically thrown into operative engagement, and when stopped thrown out of engagement thus, permitting the shaft 59 to be freely rotated by one of the motors while the other is at rest. While various constructions of clutches or a suitable ratchet mechanism may be used for this purpose, I have shown the same as consisting of an overriding ball clutch, comprising a sleeve 69 fixed 100 to the shaft 59 and the sprocket 68 loosely mounted on said sleeve, said sprocket having an annular flange 70 provided with a series of notches 71, balls 72 engaging in said notches to run upon the shaft sleeve 69, 105 the balls when the motors are idle assuming the positions at the ends of the notches, as shown in dotted lines in Fig. 14. However, as a motor is started the sprocket will have a slight free movement on the sleeve 69 110 springs 73 fixed to the shaft 59 engaging with and causing the balls 72 to roll along the walls of the notches and be wedged between the sprocket and said sleeve 69 firmly connecting the motor to the driving shaft. 115 It will be obvious that while one of the motors is operating and thus connected to the shaft, the other motor may be idle with its associated clutch mechanism disconnected, but should such latter motor be started it 120 will be operatively connected in a like manner to the shaft 59. By this construction the motors when both are operating will also be caused to operate in synchronism. Should one of the motors be operating and 125 the other be started it will at first run slowly and not pick up with the rotation of the shaft 59. However, as it has no load it will quickly pick up said shaft. It will also be obvious that should both of the motors be 130

operating and one run ahead of the other, such motor would carry all of the load of driving the propellers and thus would retard the same, while the other being free 5 from the load would readily pick up with the first motor. To prevent axial movement of the sprocket 68, one end of the hub thereof abuts against the bearing of the shaft 59 in the bracket 66, while the other end is 10 provided with a collar 74 abutting against a collar 75 fixed on the shaft 59. This collar 74 also tends to maintain the balls 72 against lateral movement.

At present when the motive power in an 15 aeroplane consists of a rotary motor it is mounted to rotate in a plane transverse to the line of flight, and the action of the motor as it revolves has a tendency to turn the aeroplane to the right or left according in 20 which direction the motor is revolving. Mounting the motor so that it revolves in a plane with the line of flight tends to maintain the aeroplane in a straight course as well as upon an even keel. Furthermore, 25 when the space at the sides between the diagonal braces 36 and between the bottom of the planes and the alighting carriage is covered as in the present instance, the motor as it revolves will throw the air through such 30 covered space and up against the bottom of the fuselage increasing the lifting function thereof.

In aeroplanes as now constructed in order 35 to crank the motor it is the usual practice to have an attendant revolve the propeller, which is a dangerous operation owing to back-firing of the motor and other causes. To overcome this disadvantage and in order to enable the aviator to crank the motor himself, I provide means whereby to crank the 40 motor from the seat of the aviator, for which purpose I provide the clutch sprocket 68 with an annular flange 76 and rotatably mount on the sprocket flange 70 a wheel 77 45 having a pair of radially projecting arms 78 the outer ends of which are beveled or inclined, and interpose balls 79 between the ends of said arms and the annular sprocket flange 76. The wheel 77 is maintained on 50 the sprocket flange by a screw threaded collar 80. Actuating levers 81 pivotally mounted on the framework and conveniently located near the seat of the aviator, are connected to the wheels 77 by means of links 82. 55 Should it be desired to start the motor all that is necessary is to give a rearward pull to the lever 81 thereby imparting rotary movement to the wheel 77, the balls being caused to ride along the inclined or curved 60 ends of the arms on said wheel by springs 83 engaging therewith and thereby wedged between the ends of the arms and the sprocket flange 76, locking the wheel 77 to the sprocket. As the lever reaches the 65 limit of its rearward movement sufficient

momentum will have been imparted to the motor to start it and it will pick up the propeller-driving shaft through its clutch mechanism in the manner heretofore described. As the clutch rotates, and the wheel 77 is 70 held stationary by the lever 81, the balls 79 will be thrown out of wedged engagement between the wheel arms 78 and the sprocket flange 76, when the lever may be returned to initial position. Should a single rearward movement of the lever 81 fail to crank the motor, by moving the lever forward it will throw the balls 79 to inoperative position and permit the wheel 77 to rotate 75 reversely without imparting motion to the clutch sprocket, when the lever 81 may again be given a rearward pull and a rotary motion imparted to the motor.

Variation may be resorted to within the scope of my invention and portions of the 80 improvements may be used without others.

Having thus described my invention, I claim:—

1. In an aeroplane, the combination with 90 the supporting surface, of a pair of propellers; a shaft extending along the forward edge of the supporting surface by which said propellers are driven; a plurality of motors, each motor having a sprocket wheel connected thereto; a plurality of overriding 95 clutches on said shaft, comprising sleeves fixed to the shaft, sprockets loosely mounted on said sleeves, the hubs of said sprockets having annular recesses provided with a series of notches, and a series of balls confined between the walls of said recesses and the sleeves and normally engaging in the recess notches; chains to connect the motor sprockets with the clutch sprockets whereby when the motors are idle the clutches will be 100 105 in inoperative position with the balls loosely engaging in the notches of the annular recesses in the sprocket hubs, but as the motors are started and rotary motion imparted to the clutch sprockets the balls will be 110 115 wedged between the walls of the annular recess and the sleeves locking the sprockets to the shafts and connecting the motors to the propellers; and springs to maintain the balls in their wedged position, substantially as and for the purpose specified.

2. In an aeroplane, the combination with 120 the supporting surface, of a pair of propellers rotating on axes parallel with the line of flight; a shaft at the forward edge of the supporting surface with its axis transverse to the line of flight and from which said propellers are synchronously gear driven; a plurality of revoluble motors mounted to revolve in a plane with the line of flight; a 125 plurality of overriding ball clutches on said shaft; and means to connect the motors with the clutches, substantially as and for the purpose specified.

3. In an aeroplane, the combination with 130

the fuselage and a pair of planes projecting laterally therefrom, of a transversely extending shaft rotatably carried at the forward edges of the planes; a pair of propellers the axes of which are in a plane with the line of flight; gears connected to said propellers; gears fixed to the ends of the shaft to mesh with the propeller gears, whereby the propellers are synchronously 5 driven from said shaft; a plurality of rotary 10 motors; hollow crank shafts fixed to the framework of the fuselage upon which the motors are mounted to rotate on axes parallel with the propeller shaft; a plurality 15 of clutches on the propeller-driving shaft; and means to connect the motors with said clutches, substantially as and for the purpose specified.

4. In an aeroplane, the combination with 20 the fuselage, of rigid planes fixed to and projecting laterally from said fuselage; a pair of propellers mounted to rotate on axes in a plane with the line of flight; a driving shaft for said propellers extending 25 transversely of the aeroplane; and means to rotatably support said propellers and shaft, comprising upwardly projecting and laterally diverging braces fixed to the fuselage, brackets fixed to the upper ends of said 30 braces in which the propellers and the ends of the shaft are journaled, and horizontal braces to one end of which the brackets are fixed, said braces extending from front to rear and secured to the bottom of the planes.

5. In an aeroplane, the combination with 35 the fuselage, of rigid planes projecting laterally from said fuselage; a pair of propellers mounted to rotate on axes in a plane with the line of flight; a driving shaft for 40 said propellers extending transversely of the aeroplane; means to rotatably support said propellers and shaft, comprising upwardly projecting and laterally diverging braces fixed to the fuselage, brackets fixed 45 to the upper ends of said braces in which the propellers and shaft are journaled, and horizontal braces to one end of which the brackets are fixed, said braces extending from front to rear and secured to the bottom 50 of the planes; a plurality of motors; and means to connect or disconnect either one or all of said motors with the driving shaft as either one or all of said motors are started or stopped.

6. In an aeroplane, the combination with 55 the fuselage, of rigid planes fixed to and projecting laterally therefrom; a pair of propellers rotatable on axes in a plane with the line of flight; a bevel gear connected to 60 each propeller; a driving shaft at the forward edges of the planes; bevel gears fixed to the ends of said shaft to mesh with the propeller gears to synchronously revolve the propellers; and means to rotatably support 65 said propellers and shaft, comprising up-

wardly projecting and laterally diverging tubular braces fixed to the fuselage, brackets fixed to the upper ends of said braces in which the propellers and the shaft are journaled, said brackets inclosing the gears, 70 horizontal braces to one end of which the brackets are fixed, said braces extending from front to rear and secured to the bottom of the planes, and cables fixed at their ends to the brackets and passing through the upwardly converging braces, substantially as and for the purpose specified. 75

7. In an aeroplane, the combination with the supporting surface, of a pair of propellers mounted to rotate on axes in a plane with the line of flight, a shaft extending 80 along the forward edge of the supporting surface operatively connected to the propellers; a pair of motors having sprocket wheels connected thereto; a pair of over-riding clutches on said shaft, comprising sleeves fixed to the shaft, sprocket wheels loosely mounted on said sleeves having a series of notches in the hubs thereof, and balls to engage in said sprocket notches and 85 confined between the walls of said notches and the shaft sleeves; and chains to connect the motor sprockets with the clutch sprockets, whereby when only one motor is operating the balls of its associated clutch 90 will be wedged between the walls of the notches and the shaft sleeve to operatively connect the motor to the shaft, the balls of the clutch of the idle motor loosely engaging in the sprocket notches, but as said motor is 100 started the balls are wedged between the walls of said notches and the shaft sleeve operatively connecting both motors to the shaft, substantially as and for the purpose specified. 105

8. In an aeroplane, the combination with the supporting surface, of propelling means rotatable on an axis in a plane with the line of flight; a shaft extending transversely of the supporting surface and operatively 110 connected to the driving means; an engine; an overriding clutch on the shaft; means to connect the engine to the shaft through said clutch; a lever; and means connected to the clutch operable by the lever to impart movement to the shaft through the clutch and thereby crank the engine. 115

9. In an aeroplane, the combination with the supporting plane, of a pair of tractor propellers, a transverse shaft, gearing connecting said shaft with the propeller shafts, a pair of engines and a pair of over-running clutches on said shaft, means to cause the engines to drive the shaft through said 120 clutches and means connected to the clutches to be actuated by the operator to impart movement to the shaft to start said engines. 125

10. In an aeroplane, the combination with the propelling means, of a driving shaft therefor; a pair of engines; a pair of over- 130

riding clutches on the shaft, one for each of said engines, each of said clutches having a laterally projecting annular sleeve; means to connect the engine with said clutches, whereby as either one or both of the engines are started the clutches will be automatically thrown into operative engagement and the engines connected with the driving shaft and the clutches automatically thrown out of engagement and the engines disconnected from the shaft when stopped; and means to crank said engines separately or jointly from the seat of the aviator, comprising a pair of wheels having radial arms and loosely mounted on the driving shaft within the clutch sleeves, the ends of which arms are beveled, balls between the ends of said arms and the clutch sleeves, and levers connected to said wheels, whereby as the levers are moved in one direction the wheels are rotated on the shaft and the balls wedged between the ends of the arms of said wheels and the clutch sleeves imparting rotary motion to the clutches and through said clutches to the engines.

11. In an aeroplane, the combination with the propelling means of a driving shaft therefor, a pair of engines, an over-running

clutch associated with each of said engines, means to effect coöperation between said clutches and said engines whereby as either of said engines are started the clutches will be automatically engaged, and whereby the clutches will be automatically disengaged from the driving shaft when the engine is stopped, means to crank said engines from the seat of the aviator comprising clutch members associated with the engines shaft and a lever in proximity to the aviator with connections to operate said shaft by means of said clutch.

12. A monoplane having a propelling mechanism including two propellers, shafts for said propellers in a horizontal plane substantially coincident with and having fixed means of support adjacent to the front edge of the supporting plane and symmetrically disposed on either side thereof, a drive shaft therefor, a power unit centrally located in said monoplane and means for starting said power unit operable by the occupant of said monoplane.

WILLARD IRVING TWOMBLY.
